UNITED STATES PATENT OFFICE

2,405,392

REFRIGERATING APPARATUS

Leonard W. Atchison, Schenectady, N. Y., assignor to General Electric Company, a corporation of New York

Application November 8, 1941, Serial No. 418,361

3 Claims. (Cl. 62—115)

1

This invention relates to refrigerating apparatus and more particularly to refrigerating apparatus for cooling a plurality of zones.

It is an object of my invention to provide improved refrigerating apparatus adapted to maintain a temperature differential between a plurality of zones.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawings in which Fig. 1 is a perspective view of a refrigerator cabinet of the domestic type embodying the principles of my invention; Fig. 2 is an enlarged view illustrating a detail of the refrigerating apparatus illustrated in Fig. 1; Fig. 3 is a fragmentary front elevational view of a refrigerator cabinet showing a second embodiment of my invention; Fig. 4 is an exploded and enlarged view of a detail of the arrangement disclosed in Fig. 3; and Fig. 5 is a fragmentary front elevational view of a refrigerator cabinet equipped with a third embodiment of my invention.

Referring to the drawings, I have provided a refrigerator cabinet 10 having a freezing chamber or zone 11 and a compartment or zone 12 maintained at a temperature suitable for the general storage of food, as 40 to 45° F. for example. In the form of my invention shown in Figs. 1 to 4 inclusive an evaporator is provided for cooling the compartment 11 and a secondary system having a cooling portion 14 is provided for cooling the compartment 12. A heat exchange device is provided for transferring heat between the primary and secondary systems. In order to maintain a predetermined differential between the temperatures of the cooling elements and of the primary and secondary systems, respectively, I have arranged a portion of one of the systems to contain a charge of a substance which is substantially unvaporizable or inert at the temperatures involved and refrigerant intermixed for providing a mixture having a different boiling point than that of the refrigerant alone. A refrigerant and a boiling point modifying substance which are miscible or mutually soluble is preferably employed, such as oil and methyl chloride or one of the refrigerants sold under the trade name Freon, for example.

The embodiment of my invention illustrated in Figs. 1 and 2 comprises a primary-secondary

2

system in which the modifying substance is introduced into a portion of the primary system. The arrangement illustrated in Figs. 3 and 4 also employs a primary-secondary system, but in this case the mixture of refrigerant and modifying substance is circulated through the secondary system. In Fig. 5 there is illustrated an arrangement in which the principles of my invention have been applied to a refrigerating system employing two series-connected evaporators 16 and 17, one of which contains the modifying substance, so that the evaporators run at different temperatures. While I have shown one evaporator within the other, my invention is equally applicable to other arrangements, as for example to evaporators disposed in different compartments which may be thermally insulated from each other. My invention is equally applicable to systems employing evaporators arranged in parallel relationship.

Describing my invention in greater detail, I have provided a refrigerator cabinet 10 of the domestic type having suitable thermally insulated walls defining the compartments or refrigerated zones. Access openings 19 and 20 to the zones or compartments 11 and 12 respectively are provided, the openings being closed by suitable thermally insulated doors 21 and 22 respectively.

In the embodiment of my invention illustrated in Figs. 1 and 2 I have provided a primary refrigerating system for maintaining a relatively low temperature in the zone or compartment 11 which may be below freezing for the storage of frozen foods and the like as well as for freezing frozen desserts, ice cubes and the like. The compartment 11 is provided with a sheet metal liner 23 of suitable material. The evaporator 13 comprises a plurality of turns of suitable material, such as copper tubing, substantially surrounding the liner 23 and preferably suitably secured in intimate thermal relation to the outer surface thereof. Any suitable system for circulating refrigerant may be provided but inasmuch as the details of such a system form no part of my present invention, illustration thereof has been omitted for purposes of clarity. The refrigerant circulating and condensing equipment may be conveniently disposed in the lower portion of the cabinet 10 and in order to provide access to the machinery compartment I have provided a panel or closure member 24. The primary system includes a liquid line 25 for conducting liquid refrigerant to a flow controlling device such as float valve 26, for example, the float valve serving in 55 a well known manner to supply liquid refriger-

ant to the evaporator 13 through a conduit 21. The last turn of the evaporator 13 is connected to a reservoir or header 28 by means of a conduit 29. A suction line 30 is provided for the return of vaporized refrigerant to the compressor unit. Whenever the level of liquid rises above the open end of conduit 30, liquid will be drawn through the suction line. Hence, when a system is employed in which lubricant is circulated, lubricant will not tend to be trapped out of the system. If it is not desired to return any liquid through the suction line, the conduit 30 may be disposed above the level to which the liquid can be expected to rise.

In operation, the compressor unit will operate to withdraw vaporized refrigerant through the suction line 30. After compression the refrigerant will be liquefied and returned to the evaporator 13 through the float valve 26. Any suitable control for the refrigerating apparatus may be provided.

The secondary system utilized for cooling the compartment 12 comprises a cooling portion 14 preferably formed from a suitable conduit such as copper tubing disposed in a plurality of turns or passes and suitably secured as by soldering to the metal liner defining the compartment or zone 12. In Fig. 1 I have shown the cooling portion associated with the two side, back and bottom walls of the compartment but any desired disposition of the cooling portion may be employed. The ends of the conduit are connected to a jacket 31 disposed in intimate thermal relationship with the tank or reservoir 28, the jacket 31 serving as a condensing portion for the secondary system. While a jacket 31 substantially surrounding a header 28 has been illustrated, any suitable heat exchanger may be employed, as a coil of tubing wound around a cylindrical member, for example. The secondary system contains a vaporizable liquid refrigerant and as the temperature within the compartment 12 increases, the refrigerant is vaporized and therefore rises to the upper turns of the cooling portion 14, finally passing to the jacket 31 through the conduit 32. The vaporized refrigerant is condensed in the condensing portion or jacket 31 and the liquid refrigerant is returned to the cooling portion 14 through the conduit 33.

In order to maintain a predetermined temperature differential between the cooling element 13 and the cooling portion or element 14 of the secondary system with the temperature of element 14 higher than that of element 13, I provide a substance which will raise the boiling point of the refrigerant in the reservoir 28. The refrigerant and substance or material used are preferably miscible or mutually soluble, that is, readily soluble in each other in nearly all proportions. The substance also should be noncongealable at temperatures normally encountered in the operation of refrigerators and should not be easily vaporized at the temperatures encountered in the refrigerating cycle. For example, the modifying substance or material may be oil and the refrigerant methyl chloride or a refrigerant known under the name of Freon. The modifying substance need not be a liquid, it being sufficient that the substance be sufficiently dispersable through the refrigerant to vary the boiling point thereof to the desired amount. The differential in temperature will be a function of the proportions of the substance and the refrigerant and also of the temperature at which the cold storage compartment is run. Thus, I may

utilize an arrangement comprising a plurality of evaporators maintained at a predetermined temperature differential while employing the same refrigerant in each evaporator. The refrigerant vaporized in the primary system will be drawn off through the suction line 30 while practically all of the substance, such as oil, below the level of the suction line, will remain in the header 28 inasmuch as it is nonvaporizable or substantially so at the temperatures involved. Since the refrigerant supplied to the evaporator through the float valve 26 is substantially free of the substance, the temperature of the cold storage evaporator can be held at one temperature and that of the reservoir or header 28 at a higher temperature and accordingly the condensing effect on the vaporized refrigerant in the jacket 31 will be less than if pure refrigerant were contained in the reservoir.

In the embodiment of my invention shown in Figs. 3 and 4, the differential establishing mixture is employed in the secondary system rather than in the primary system. The cooling portion 14 of the secondary system communicates with a mixing chamber or header 34 and the mixture of refrigerant and differential providing substance occupies the entire cooling portion, a liquid level being established in the header as indicated by the numeral 34a. A condensing portion 35 communicating with the header 34 above the liquid level therein is secured in good heat exchange relationship with the primary evaporator 13 as by means of threaded fastening means 42. The condensing portion 35 may take any desired form. In the arrangement illustrated in Fig. 4, the condensing portion comprises a plurality of substantially U-shaped loops 36, the ends of the loops communicating with the upper portion of the header 34. The loops 36 are arranged to engage the liner 23 of the evaporator 13 between the turns comprising the evaporator 13. In order to secure the condensing portion to the primary evaporator, I have illustrated a pair of metal strips 37 suitably secured to the loops 36 as by soldering or welding. The strips are provided with tapped openings 38 for the reception of suitable screws 42 extending through corresponding openings in the bottom wall of the lining 23.

The principle of operation is similar to that previously described. Refrigerant will be vaporized by the absorption of heat from the compartment 12 and rise into the condensing portion 35 whereas the unvaporizable substance will remain in the turns of the cooling portion 14 and in the header 34. The vaporized refrigerant will be condensed by the heat exchange with evaporator 13 and the condensed liquid will return to the header 34 and dissolve in the liquid solution.

In Fig. 5 I have shown a series-connected system. In the form shown, there is illustrated an inner evaporator 17 similar in construction to the evaporator 13 shown in Figs. 1 to 4 inclusive and an outer evaporator 16 formed from sheet metal and provided with suitably formed laterally extending refrigerant passages 16a communicating at either end thereof with headers 39, the headers being joined by an equalizing connection 40. Substantially pure refrigerant is supplied to the inner evaporator 17 by the float valve 26. An extension of the last turn of the evaporator 17, indicated by the numeral 18, joins the evaporators and serves to inject refrigerant into the outer evaporator. The boiling point modifying mixture is provided in the outer evaporator 16. Liquid refrigerant supplied to evaporator 17 absorbs

heat from zone 11, and liquid as well as vaporized refrigerant is injected into evaporator 16 through conduit 18 and becomes mixed with or dissolved in the mixture in evaporator 16. Vaporized refrigerant from the evaporator 16 collects in the headers 39 and is drawn off through the suction line, leaving the nonvaporizable differential producing substance behind. Thus, substantially pure refrigerant is supplied the inner evaporator 17 so that the inner evaporator is cooled by nearly pure liquid refrigerant.

In order to maintain the freezing compartment 11 as cold as possible for any given control setting, and to prevent the temperature of the evaporator 17 from exerting an influence on the temperature of the air circulating through the compartment 12 I may close the rear end of the compartment 11 in any suitable manner, not shown, and provide a suitably hinged door 42' to close the front end thereof.

While I have shown a particular embodiment of my invention I do not desire my invention to be limited to the particular construction shown and described and I intend in the appended claims to cover all modifications within the spirit and scope of my invention.

What I claim as new and desire to secure by Letters Patent of the United States is:

1. Refrigerating apparatus comprising means for maintaining a first zone at a relatively low temperature and means for maintaining a second zone at a higher temperature, both said means being arranged to be connected for operation by the same condensing equipment, each of said means containing vaporizable refrigerant, the one of said means associated with said second zone having a portion thereof containing liquid refrigerant and a material which is substantially unvaporizable at the temperatures involved and miscible with the liquid refrigerant, the mixture having a higher boiling point than that of the refrigerant alone and thereby facilitating the operation of said apparatus to maintain a temperature differential between said zones, means for conducting substantially pure liquid refrigerant to said portion and means for removing vaporized refrigerant from said portion.

2. Refrigerating apparatus comprising means for maintaining a first zone at a relatively low temperature and means for maintaining a second zone at a higher temperature, both said means being arranged to be connected for operation by the same condensing equipment, each of said means containing vaporizable refrigerant, the one of said means associated with said second zone having a portion thereof containing liquid refrigerant and a noncongealable material which is substantially unvaporizable at the temperatures involved and miscible with the liquid refrigerant, the mixture having a higher boiling point than that of the refrigerant alone and thereby facilitating the operation of said apparatus to maintain a temperature differential between said zones, means for conducting substantially pure liquid refrigerant to said portion and means for removing vaporized refrigerant from said portion.

3. In refrigerating apparatus comprising means for maintaining a first zone at a relatively low temperature and means for maintaining a second zone at a higher temperature, both said means being arranged to be connected for operation by the same condensing equipment, each of said means containing vaporizable refrigerant, the one of said means associated with said second zone

having a portion thereof containing and retaining a material which is substantially unvaporizable at the temperatures involved and miscible with the liquid refrigerant, the mixture having a higher boiling point than that of the refrigerant alone and thereby facilitating the operation of said apparatus to maintain a temperature differential between said respective zones, means for conducting substantially pure liquid refrigerant to said portion and means for removing vaporized refrigerant from said portion.

4. Refrigerating apparatus comprising a primary and a secondary refrigerating system for cooling a plurality of zones to different temperatures and means providing a heat conducting path for transferring heat between said systems, a vaporizable refrigerant in each of said systems and a substance which is substantially unvaporizable at the temperatures involved and miscible with the refrigerant in said secondary system, the mixture having a higher boiling point than that of the refrigerant alone to facilitate the operation of said secondary system at a higher temperature than that of said primary system, said secondary system being arranged to retain said substance therein.

5. Refrigerating apparatus comprising a cooling element, said element comprising a first evaporator, a second evaporator within said first evaporator and spaced therefrom, said first evaporator being arranged for operation at a higher temperature than said second evaporator, a vaporizable refrigerant in each of said evaporators, means for circulating refrigerant through said evaporators in series, a substance which is substantially unvaporizable at the temperatures involved in said first evaporator and which is miscible in said refrigerant for raising the boiling point of the mixture in said first evaporator in order to facilitate the operation of said first evaporator at a higher temperature than that of said second evaporator.

6. A cooling element for use in refrigerators to provide zones operating at different temperatures and comprising a first evaporator, a second evaporator within said first evaporator and spaced therefrom, said first evaporator being arranged for operation at a higher temperature than said second evaporator, a vaporizable refrigerant in each of said evaporators, means for circulating refrigerant through said evaporators in series, a substance which is substantially unvaporizable at the temperatures involved in said first evaporator, said substance being soluble in said refrigerant for raising the boiling point of the solution in said first evaporator in order to facilitate the operation of said first evaporator at a higher temperature than that of said second evaporator.

7. Refrigerating apparatus comprising a cooling element, said element comprising a pair of evaporators for operation at different temperatures, means for circulating refrigerant through said evaporators in series, and a substance which is substantially unvaporizable at the temperatures involved being disposed in one of the evaporators, said substance being miscible in said refrigerant for raising the boiling point of the solution in said one evaporator in order to facilitate the operation of said one evaporator at a higher temperature than the other evaporator, said one evaporator being arranged to retain said substance therein.

8. Refrigerating apparatus comprising two evaporators for operation at different temperatures, a common means for supplying refrigerant

to both said evaporators and for withdrawing vaporized refrigerant therefrom, and a substance which is substantially unvaporizable at the temperatures involved disposed in one of said evaporators, said substance being miscible in said refrigerant for raising the boiling point of the liquid

in said one evaporator in order to facilitate the operation of said one evaporator at a higher temperature than the other evaporator, said one evaporator being arranged to retain said substance therein.

LEONARD W. ATCHISON.
